N. W. DICKERSON.
SAFETY APPARATUS FOR MINE RAILWAYS.
APPLICATION FILED NOV. 12, 1908.

911,298.

Patented Feb. 2, 1909.

UNITED STATES PATENT OFFICE.

NORVAL W. DICKERSON, OF DERWENT, OHIO.

SAFETY APPARATUS FOR MINE-RAILWAYS.

No. 911,298.

Specification of Letters Patent.

Patented Feb. 2, 1909.

Application filed November 12, 1908. Serial No. 462,376.

To all whom it may concern:

Be it known that I, NORVAL W. DICKERSON, a citizen of the United States, residing at Derwent, in the county of Guernsey and 5 State of Ohio, have invented new and useful Improvements in Safety Apparatus for Mine-Railways, of which the following is a specification.

My present invention relates to safety apparatus for use in connection with mine railways and elevators; and it consists in the 10 simple, compact, durable and otherwise practically-advantageous apparatus herein-after described and particularly pointed out 15 in the claims appended.

In the drawings, accompanying and forming part of this specification: Figure 1 is a plan view illustrating the apparatus constituting a practical embodiment of my invention as properly arranged relative to an elevator shaft and a railway leading thereto; the parts of the apparatus being shown 20 in their normal positions—*i. e.*, the positions they occupy when the elevator car or cage is 25 above the landing on which the apparatus is arranged. Fig. 2 is an elevation of that end of the apparatus adjacent the elevator shaft. Figs. 3, 4 and 5 are enlarged detail views illustrative of one of the car-catchers 30 of the pair adjacent the elevator shaft.

Similar letters designate corresponding parts in all of the views of the drawings, referring to which:

A is an elevator shaft. 35 B is an elevator car or cage, and C C are the rails of a railway, leading to the shaft and preferably, though not necessarily, pitched slightly downward toward the same.

In putting my invention into effect I provide a longitudinal-central rock-shaft D, 40 mounted in suitable bearings between the rails C, and having a trigger E, of crank form, at its end adjacent the elevator shaft, and also having levers F and G at intermediate points of its length.

H H are rock-shafts journaled and movable endwise in bearings b and c, fixed at the outer sides of the rails C, and I I are rock-shafts journaled and movable endwise in the 50 bearings c and also in bearings d and having their forward ends opposed to the rear ends of the shafts H, as shown in Fig. 1. At points adjacent the forward bearings b the shafts H are provided with flanges e and flat-portions f, best shown in Figs. 3 and 4, and between the said flanges e and the bearings b

coiled springs J are interposed; the said springs surrounding the shafts and having for their office to cushion the blow when the wheels of a car bring up against either pair 60 of the catchers hereinafter described.

K K are forward car catchers—*i. e.*, those comprised in the pair adjacent the elevator shaft, and L L are the rear car catchers or those located comparatively remote from the 65 elevator shaft. The forward catchers C are riveted or bolted to the flat shaft-portions f, and to said shaft portions are also riveted or bolted depending arms K'. The rear catchers L are formed integral with or suitably 70 fixed to the shafts I in any approved manner, and are provided with depending arms L'; and in this connection I would have it understood that the catchers K and L may be connected to their shafts in any manner 75 consonant with the purpose of my invention without involving departure from the scope thereof.

Intermediate the ends of the lever F and the arms K' of the catchers K are link rods 80 M, Figs. 1 and 2, and intermediate the ends of the lever G and the arms L' of the catchers L are link rods N, while fixed on the shaft D is a weighted arm P, which latter has for its office to return the catchers K and 85 L to and normally retain the same in the positions illustrated.

With the parts in the positions shown in Fig. 1, it will be manifest that a car located on the rails C between the catchers K and 90 the catchers L will be prevented by said catchers K from passing to the elevator shaft. It will also be manifest that when the descending elevator nears the landing a part thereof will strike the trigger E and in 95 that way rock the shaft D in the direction indicated by arrow so as to move the catchers K outwardly from over the rails C, and the catchers L inwardly to positions above the rails. With this done the forward 100 car is obviously free to move on the elevator car, while a following car will bring up against the catchers L. Then when the elevator car ascends from the landing, the weighted arm P will serve to return the 105 parts to the positions shown in Fig. 1, whereupon the said following car will be released by the catchers L and permitted to move forward until it brings up against the catchers K in which latter position it will be 110 securely retained until the elevator car again reaches the landing.

It will be gathered from the foregoing that my novel apparatus may be depended on to prevent a car passing to the elevator shaft when there is no car at the landing, 5 and that the apparatus is simple and compact and is well adapted to withstand the rough usage to which apparatus of corresponding character is ordinarily subjected.

The construction herein illustrated and 10 described constitutes the best practical embodiment of my invention of which I am cognizant, but it will be understood that in the future practice of the invention such changes in the form, construction and relative arrangement of parts may be made as 15 fairly fall within the scope of my invention as defined in the claims appended.

Having described my invention, what I claim and desire to secure by Letters-Patent, 20 is:

1. In a safety apparatus, the combination of an elevator shaft, a landing, an elevator car movable in the shaft, a forward car catcher located on the landing and having an 25 arm, a rear car catcher also located on the landing and having an arm, a rock-shaft having levers and also having a trigger which latter is adapted to be engaged and moved by the elevator car, and connections between 30 the levers and the arms of the catchers, all arranged to move the catchers synchronously in opposite directions.

2. In a safety apparatus, the combination of an elevator shaft, a landing, an elevator car movable in the shaft, a forward car catcher located on the landing and having an arm, a rear car catcher also located on the landing and having an arm, a rock-shaft having levers and also having a trigger which latter is adapted to be engaged and moved by the elevator car, connections between the levers and the arms of the catchers arranged to move the catchers synchronously in opposite directions, and a spring arranged to cushion a blow against either catcher. 40

3. In a safety apparatus, the combination of an elevator shaft, a landing, railway rails thereon, an elevator car, longitudinally disposed bearings arranged alongside the rails, rock-shafts journaled in said bearings and having abutments, springs interposed between the abutments and bearings, catchers fixed on the rock-shafts and having arms, a third rock-shaft arranged intermediate the rails and having a trigger and also having 50 levers, and rod connections between the said levers and the arms of the catchers.

In testimony whereof I have hereunto set my hand in presence of two subscribing witnesses.

NORVAL W. DICKERSON.
